UNITED STATES PATENT OFFICE.

LEE ROY JOHNSON, OF BRENHAM, TEXAS.

PROTECTING DEVICE.

Application filed January 31, 1925. Serial No. 6,098.

To all whom it may concern:

Be it known that I, LEE ROY JOHNSON, a citizen of the United States, residing at Brenham, in the county of Washington and State of Texas, have invented new and useful Improvements in Protecting Devices, of which the following is a specification.

This invention relates to protecting devices for post offices, railway mail or express cars, banks and similar places and has for an object the provision of means whereby one or more guns may be fired from a point remote from the gun and without the use of the hands of the person firing, so that the hands may be held above the head to disarm suspicion and the gun or guns discharged without attracting attention of the robbers or hold-up men until the actual firing occurs.

To this end, the invention provides electrically controlled means for discharging one or more guns with the latter placed at a point remote from the controlling means and hidden or camouflaged so that they will not be apparent to persons unfamiliar with the same.

With the above and other objects in view, the invention further includes the following novel features and details of construction, to be hereinafter more fully described, illustrated in the accompanying drawings and pointed out in the appended claims.

In the drawings:

Figure 1 is a perspective view illustrating the invention arranged for use.

Figure 2 is a horizontal sectional view taken substantially on the line 2—2 of Figure 1.

Figure 3 is a section taken substantially on the line 3—3 of Figure 2.

Figure 4 is a fragmentary elevation looking at the breech ends of the guns with the hammer shaft and hammers removed.

Figure 5 is a detail section on the line 5—5 of Figure 1.

Referring to the drawings in detail where-in like characters of reference denote corresponding parts, the guns whose barrels are indicated at 10 are designed to be supported in a frame 11 contained within a housing 12,

the guns being horizontally arranged at a height approximately equal to the height of the stomach of an average man. The base 13 of the housing 12 is supported by a panel 14 and the latter is hingedly secured as shown at 15 to a wall or suitable support

16. The panel 14 is hinged at one end and

its opposite end may be locked or otherwise detachably connected to the support 16 in a manner to permit said panel being swung horizontally outward. The end of the housing abutting the support 16 is open, while the outer end of the said housing comprises a frame 17 which carries a paper or other covering 18 upon which may be printed suitable indicia or information. For example the closure 18 may contain post office rules so that the housing would not be of a suspicious character.

The inner ends of the gun barrels 10 are adapted to receive a shell or cartridge 19 which is held in place by means of a breech bar 20. This bar is slidingly secured as indicated at 21 to the frame 11 and carries notched extensions or breech blocks 22 which engage behind the shells or cartridges 19 to hold the latter within the firing chamber at the inner end of the gun barrel. The shells or cartridges are inserted or removed from the barrel by moving the breech bar longitudinally to uncover the inner ends of the barrels.

Hingedly mounted upon the base 13 adjacent each barrel 10 as indicated at 23 is a guide bracket 24. These brackets have relatively wide bases so as to provide oppositely extending flanges to which the hinges 23 are secured and which are engaged by pivotally movable latches 25 mounted upon the bases and by means of which the guide brackets 24 are held in position. Slidably mounted in the brackets 24 are firing pins 26 which are adapted to operate through the notch of the breech blocks 22 to engage the shell or cartridges 19. The firing pins are provided with heads 27 between which and the brackets 24 are positioned springs 28 which serve to yieldingly force the pins in a direction away from the shells or cartridges 19.

Rotatably mounted in brackets 29 supported upon the base 13 is a hammer shaft 30. This shaft has secured thereon a plurality of hammers 31 whose heads 32 are arranged to engage the heads 27 of the firing pins 26. Movement of the hammers in one direction is limited by a stop 33 which extends transversely of the hammers and is supported by arms 34 which are carried by the brackets 29. Mounted upon one end of the shaft 30 is a fast and loose pulley 35 and 36 respectively.

Mounted upon the support 16 above the

housing 12 is a shaft 37 which is rotatable in bearings provided at the outer ends of bearing brackets 38. The shaft 37 has secured thereon a pulley 39 over which passes a belt 40, the latter being adapted to engage either the pulley 35 or 36. The belt operates through a stationary guide 41 and a laterally movable slidingly mounted guide 42, the latter operating in a guide 43 mounted upon the support 16 and being adapted to shift the belt 40 so as to cause the latter to operate either the fast or loose pulley 35 or 36. The belt passes through a slot 44 provided in the housing 12.

Secured to the slidingly mounted guide 42 is one end of a wire or cable 45, the opposite end of which extends into a cabinet 46 which is located at some suitable point remote from the housing 12. The end of the cable 45 which enters the cabinet 46 is secured to one end of an L-shaped lever 47. This lever is pivotally mounted as shown at 48 within the cabinet and has pivotally connected thereto one end of a foot pedal 49 which extends through the top of the cabinet 46. A spring 50 secured to the lever 47 serves to yieldingly resist pivotal movement of the latter in one direction. A spring 51 which is secured to the slidingly mounted guide 42 also serves to resist movement of the slide in one direction and to hold the said slide in position to guide the belt over the loose pulley 36.

The shaft 37 is driven from an electric motor 52 by any suitable means, the means shown consisting of grooved pulleys 53 and 54 and a belt 55. Current for the operation of the pulley 52 may be received from any suitable source, while connected in circuit with the motor and controlling the operation of the same is a switch 56. The switch 56 includes pivotally mounted blades 57 to which is connected a link 58, the latter being pivotally secured to a hingedly mounted panel S provided in the top of the cabinet 46. The switch 56 may be connected with a source of current by means of conductor wires 59, while wires 60 connect the switch with the motor 52.

Also pivotally mounted within the cabinet 46 as shown at 61 is a bell crank lever 62, one arm of which is positioned beneath and engaged by the panel S. The other arm of the lever 62 is connected to one end of a cable 63 which passes over guide pulleys 64 and is connected to the inner end of a plunger 65. The plunger 65 is guided through the top of the cabinet 46 and through a guide bracket 55 within the cabinet, a spring 67 which surrounds the plunger acts to yieldingly force the latter inward. The outer end of the plunger is provided with a pedal 68.

It is of course apparent that one or more of the devices may be positioned at advan-

tageous points with the cabinets preferably hidden in conveniently accessible places. In the event of a "hold up", a clerk or other person will press downward with his foot upon the panel S so as to close the switch 56, downward movement of the panel rocking the bell crank lever 62 upon its pivot so as to move the plunger 65 outward. When the switch 56 is closed a circuit will be completed through the motor 52 to drive the shaft 37, the belt 40 operating over the loose pulley 36. When the hold up men are in the line of fire of the guns, the pedal 49 is depressed so that the cable connection 45 will move the sliding guide 42 to shift the belt on to the fast pulley 35. The shaft 30 will then be operated so that the hammers 31 will swing around to strike the heads of the firing pins 26 and explode the cartridges or shells 19. By pressing upon the pedal 68, the bell crank 62 is operated through the cable 63 to raise the panel S and open the switch 56 and stop the operation of the motor 52.

In loading the guns, the panel 14 is unlocked and swung outward upon the hinges 15. The breech slide 20 is moved laterally to uncover the breech ends of the gun barrels 10. The cartridges are then slipped in place and the breech slide operated to move the breech blocks in proper position. In order to insert the cartridges, the guide brackets 24 of the firing pins are swung laterally downward to the position shown in Figure 4, the latches 25 being moved pivotally to release the brackets. After the cartridges are inserted the brackets are returned to their normal position and the latches operated to hold the brackets in place.

The invention is susceptible of various changes in its form, proportions and minor details of construction and right is herein reserved to make such changes as properly fall within the scope of the appended claims.

Having described the invention what is claimed is:—

1. A device of the character described comprising a gun, normally disengaged means for operating the hammer of the gun to discharge the latter, electrically operated means for actuating the hammer operating means and means remote from the gun for engaging the hammer operating means with the hammer.

2. A device of the character described comprising a housing, guns positioned within the housing, a hammer shaft common to all of the guns and rotatable to discharge the latter, a normally disengaged hammer shaft operating mechanism, means remote from the housing for controlling the operation of the hammer operating mechanism and means also remote from the shaft where-

- by the mechanism may be engaged with the hammer shaft.
3. A device of the character described comprising a housing, guns positioned within the housing, a hammer shaft common to all of the guns and rotatable to discharge the latter, a normally disengaged hammer shaft operating mechanism, means remote from the housing for controlling the operation of the hammer operating mechanism and means remote from the shaft and operable simultaneously with the mechanism controlling means for engaging the operating mechanism with the hammer shaft.
- 10 4. A device of the character described comprising a housing, guns positioned within the housing, a hammer shaft common to all of the guns and rotatable to discharge the latter, a normally disengaged hammer shaft operating mechanism, means where-
- 15
- 20

by said mechanism may be engaged with the shaft, means for controlling the operation of the mechanism and means associating the shaft engaging means and the mechanism controlling means to provide for simultaneous operation.

5. A device of the character described comprising a housing, guns disposed within the housing, normally inactive means common to all of the guns and disengaged therefrom, whereby the latter may be simultaneously discharged, means remote from the housing for rendering the gun discharging means active and means operable subsequently to the operation of the last mentioned means for engaging the gun discharging means with the guns.

In testimony whereof I affix my signature.

LEE ROY JOHNSON.
